UNITED STATES PATENT OFFICE.

JACOBUS HAAG, OF AMSTERDAM, NETHERLANDS.

APPARATUS COMPRISING PERKINS TUBES.

Application filed January 26, 1923. Serial No. 615,109.

To all whom it may concern:

Be it known that I, JACOBUS HAAG, a subject of the Queen of the Netherlands, residing at Amsterdam, Netherlands, have invented certain new and useful Improvements in Apparatus Comprising Perkins Tubes, of which the following is a specification.

The object of my present invention is to provide an improved construction of apparatus for the generation of steam or pressure vapor which employs Perkins tubes, such as is disclosed in the Perkins United States Patent No. 529,304, comprising hermetically closed tubes partly filled with suitable liquid and adapted, when heated at one end, to emit heat at the other end. The annexed drawing shows apparatus of this type with an embodiment of my present invention.

On the drawing, Figure 1 shows somewhat diagrammatically a vertical section of a steam boiler provided with Perkins tubes, whereas Figure 2 shows on an enlarged scale a vertical section of the upper portion of a Perkins tube closed by means of a screw-threaded plug. As a matter of course the invention may also be embodied in ovens, furnaces and any other apparatus in which Perkins tubes are used to heat an enclosed space.

In Figure 1, A is the furnace, B is the boiler to which heat produced in A is to be transmitted.

In accordance with my present invention, the Perkins tube 4 passes tightly both through the top plate 3 and through the bottom plate 7 of the boiler, and the top end of the tube is hermetically closed by means of a screw-threaded cap 8 screwed on male thread 9 of the tube. This cap could be replaced with equal advantage by a screw-threaded plug, adapted to be received by female thread in the tube. Perfectly tight joints between the tube 4 and the plates 3 and 7 are obtained by expanding the tube at these junctures.

By expanding the tubes in accordance with my present invention I am enabled to support the tubes in fluid tight engagement with the container walls without necessitating the use of conical or other enlargements on the tubes, or the provision of enlarged holes in the tube plates such as characterize the prior art constructions. As a result I can employ straight drawn tubing for making the tubes, thus not only simpli-

fying the construction and the cost of manufacture of the tubes as well as the tube sheets, but also the installation of the tubes. Furthermore, by avoiding the use of enlarged holes in the tube sheets or container walls, weakening of the walls is obviated, therefore more tubes may be installed in for a given area of container wall and the heating capacity of the apparatus greatly increased. After the expansion of the tubes, the apparatus may be water tested, and the Perkins tubes may then be filled and closed. These operations are effected outside the boiler, so that they do not offer any difficulty. Moreover, in the event of leakage occurring between a tube and a boiler plate, repair may be effected even whilst the boiler is in use, inasmuch as access may be obtained to the interior of the tube by removing the closure 8 and a tube expander inserted for the purpose of expanding the wall of the tube at the point of leakage through the boiler wall 3 or 7. During this operation the tube may be cooled by water admitted thereinto. As will be understood the top end of the tube 4 should extend sufficiently far beyond the top plate 3 to avoid injury, during the operation of expansion, to the screw-thread provided for the reception of the cap or the plug, as shown.

My novel construction also permits of checking the operation of the tubes. For instance, I may provide the screw-cap or screw plug of the tube with a small pipe closed at its bottom end and adapted to receive a thermometer. By this means, I am enabled to check the operation of each tube separately and obtain the maximum efficiency of the apparatus. This construction is illustrated in Figure 2. The open end of tube 4 is here closed by a screw plug 10 having a central hole for receiving a small pipe 11, the closed bottom end of which protrudes into the vapour space of tube 4. This pipe serves to receive a thermometer 12.

What I claim is:

1. Apparatus for the indirect generation of steam by the use of hermetically sealed tubes which are partially filled with a liquid and which traverse a heating chamber, characterized by the ends of said tubes projecting beyond the walls of said chamber, one of said projecting ends of each tube being open, the walls of said tube being expanded into contact with the walls of said

chamber to form therewith a steam tight joint, and a removable closure for hermetically sealing said projecting open end.

2. Apparatus for the indirect generation
5 of steam by the use of hermetically sealed tubes which are partially filled with a liquid and which traverse a heating chamber, characterized by the ends of said tubes projecting beyond the walls of said heating chamber,
10 one of the projecting ends of each tube being open and provided with screw threads, a removable closure to engage with said

screw threads and hermetically seal said open end of said tube, the walls of said tubes being expanded into contact with the walls 15 of said chamber to form therewith a steam tight joint, and the screw threaded ends of said tubes projecting beyond the expanded portions thereof a sufficient distance to prevent distortion of the screw threads by the 20 expansion of said tubes.

In testimony whereof I affix my signature.

JACOBUS HAAG.
